UNITED STATES PATENT OFFICE.

MAURICE LACHMAN, OF NEW YORK, N. Y., ASSIGNOR TO LACHMAN MANUFACTURING COMPANY, OF NEW YORK, N. Y., A CORPORATION OF DELAWARE.

KNOCKDOWN CONTAINER.

1,133,293.

Specification of Letters Patent. Patented Mar. 30, 1915.

Application filed April 12, 1913. Serial No. 760,591.

To all whom it may concern:

Be it known that I, MAURICE LACHMAN, a citizen of the United States, and a resident of New York, in the county of New York and State of New York, have invented certain new and useful Improvements in Knockdown Containers, of which the following is a specification.

My present invention relates to shipping receptacles or containers especially those in which the body portion is made of non-metallic material like paper, pulp or a similar substance.

The invention more particularly relates to such containers when made in knockdown form.

The main object of the invention is to provide a knockdown container or receptacle which will be cheap, light and uniform in weight with other containers of the same style and size and at the same time provide a construction which can be quickly and easily assembled without any special tools being necessary.

It is a further object to maintain simplicity with rigidity and strength in the assembled structure.

In parts remote from manufacturing centers large orchards, mills, etc., are usually located and the expense of obtaining containers or receptacles of the usual type in which to ship their goods is very great owing to the bulk of the containers which are shipped to such places empty. Owing to the increasing cost of lumber as well as the variation in weight, knockdown wooden barrels and boxes are fast becoming prohibitive while in knockdown metal containers the cost of the metal as well as its weight makes the use of this type very limited, all metal containers also being unsuitable for shipping many articles.

According to this invention the main body portion of the container is formed of paper, strawboard or some similar non-metallic material made in rigid sections so that the parts can be shipped to the user "knocked down." By employing paper of great rigidity, a light yet strong body is provided and one which will be uniform in weight for all containers of the same size and shape. Simple means are also provided for assembling the sections together and fastening in the heads without the use of any special tools or implements. This latter feature is

accomplished by employing a locking strip of novel form which serves to unite the sections of the body together, fasten in the heads and provide strengthening stay members for the container.

The invention consists in the novel parts, combinations of parts and details of construction of the knockdown container hereinafter more particularly described and then specified in the claim.

In the accompanying drawings, Figure 1 is a side elevation and partial section of a knockdown container constructed in accordance with this invention in one of its forms. Fig. 2 is an enlarged horizontal section of the same taken on the line 2-2 Fig. 1 and looking upward in the direction of the arrows. Fig. 3 is a fragmentary cross-section taken on the line 3-3 Fig. 2. Fig. 4 is a perspective view of the preferred form of locking strip.

The invention is illustrated and will be described herein as applied to a keg or barrel, the body portion of which is formed of a plurality of duplicate sections 1. Each section comprises a panel of straw-board, paper or some similar paper-like material formed in any suitable or desirable manner. A preferred manner of forming these sections is by forming a cylinder of a number of layers of paper superimposed on each other, preferably by spinning, and compressed into a very solid mass to any desired thickness, the various layers being united by suitable cement, glue or other adhesive whereby a very rigid wall is attained. After the cylinder is formed it is cut longitudinally into any desired number of segments to form the body sections 1. By following this method it is assured that the sections will at all times retain their shape and will exactly mate up to form a perfect cylindrical body. The specific manner of forming the cylinder or the separate sections forms no part of this invention and further description will be dispensed with.

2 indicates the locking member for joining the separate sections 1 together. Said member is preferably made up from a single strip of metal formed into an I-shape in cross-section. The I-shape is formed by bending each side of the metal longitudinally back upon itself to form flanges 3 and then at right angles thereto to form the web 4 of the I after which the two free edges 5

are bent at right angles to the web and in opposite directions, whereby the strip resembles two U-shaped pieces, the bases of which are disposed back to back so that two grooves or channels opening in opposite directions are provided along the two longitudinal edges of the member. The web portion and the flanges 5 are cut away for a greater or less distance from each end of the strip 2, so that for a distance from each end the flanges 5 form a flat extension 6.

When it is desired to assemble the container the locking strips 2 are slid vertically down between the sections 1 in such manner that the web 4 is interposed between adjacent edges of two sections and the flanges 3 and 5 bear on the outer and inner periphery of such adjacent edges. In this manner the raw edges of the paper sections 1 are protected against tearing or mutilation.

7 indicates a continuous metal hoop or band which might, if desired, be also employed at each end of the body surrounding the separate sections 1. Preferably the band 7 is provided with an inwardly projecting flange which rests on the end of the body to protect the raw edge of the paper against mutilation.

The heads for the container, one being provided at each end of the body, may be of any desired construction, the one herein shown comprising a paper disk 9 forming the main closure of the head, said disk being seated and held in an annular metal rim 10 in any suitable manner. The metal rim 10 is also provided with a flange 11 which seats on the end of the body of the container.

The extensions 6 of the locking strips 2 preferably pass up around the outside of the band 7 and are turned over the flange 11 as shown, thus locking the heads to the body, the strips 2 also forming stay members for strengthening the container as a whole. The web 4 and flanges 5 of the locking strips are cut away sufficiently to allow the rim 10 to enter the body and if desired the rim may rest on the ends of the web and flanges 5 which may form an additional seat therefor.

It will be understood that various modifications of the invention as specifically disclosed herein might be resorted to without departing from the spirit thereof.

What I claim as my invention is:

A knock-down container comprising a plurality of sections adapted to form a body, longitudinal stay-members comprising metallic devices of substantially I-cross-sections the width of the webs of which is substantially the same as the thickness of a section, end hoops fitting over the ends of all of said sections and having a depending flange, a head provided with a flange lapping the ends of the body, and hooks formed by extending the bases of the I cross-section stays and bending said bases over a portion of said head to retain said head within the container.

Signed at New York in the county of New York and State of New York this 10th day of April A. D. 1913.

MAURICE LACHMAN.
